DESIGN FOR A GLASS BOTTLE

Lawrence J. Kihn, Pittsburgh, Pa., assignor to J. T. & A. Hamilton Company, a corporation of Pennsylvania

Application December 28, 1934, Serial No. 54,621

Term of patent 14 years

To whom it may concern:

Be it known that I, Lawrence J. Kihn, a citizen of the United States, residing in Pittsburgh, in the county of Allegheny and State of Pennsylvania, have invented a new, original, and ornamental Design for a Glass Bottle, of which the following is a specification, reference being had to the accompanying drawing, forming part thereof.

My design relates to the general appearance of the glass bottle, as produced by its conformation and external ornamentation.

In the drawing: Fig. I is a front elevation of a glass bottle showing my new design; Fig. II is a side elevation of the glass bottle shown in front elevation in Fig. I; and Fig. III is a rear elevation of the said glass bottle.

I claim:

The ornamental design for a glass bottle, substantially as shown.

LAWRENCE J. KIHN.
